Attorney

UNITED STATES PATENT OFFICE

ROY G. HUBBARD, OF HASTINGS, MICHIGAN

SHIPPING RECEPTACLE

Application filed April 24, 1928. Serial No. 272,479.

The present invention relates to improvements in shipping receptacles, and has reference more particularly to a receptacle for use in conjunction with the transit of mail.

At the present time, letters are tied into a bundle or package for transfer in the mails, and this requires the expenditure of considerable time in the tying and opening of a package, and furthermore no protection is afforded the letters while in transit.

It is therefore one of the principal aims of the present invention to provide a receptacle for receiving letters that are to be sent from one point to the other, the receptacle being of such construction as to protect the letters from any other foreign matter, as well as against being damaged while in transit.

A further object is to provide a shipping receptacle of the above mentioned character which is simple in construction, inexpensive, strong and durable and further well adapted to the purpose for which it is designed.

Other objects and advantages of the invention will become apparent from the following description when taken in connection with the accompanying drawing.

In the accompanying drawing wherein like reference characters indicate corresponding parts throughout the same:

Figure 1 is a front side elevation of the shipping receptacle embodying my invention, parts being broken away.

Figure 2 is an end elevation thereof with parts broken away, and

Figure 3 is a fragmentary top plan view.

In the drawing wherein for the purpose of illustration is shown the preferred embodiment of my invention, the numeral 1 designates generally my improved shipping receptacle, the same comprising a substantially rectangular shaped body 2 that is formed preferably from a piece of canvass and which includes a bottom, side and end walls, it being understood of course that any appropriate means may be provided for retaining the shape of the canvas body.

In addition, leather corner pieces 3 are provided. The front side of the canvas body is formed with an enlarged opening

over which is disposed a piece of celluloid 4. The purpose of this transparency is to provide a means whereby a person can readily view the contents of the receptacle. A rectangular frame-like structure 5 is secured 55 on the outer face of the front side of the canvas body by stitching and the inner edge portion of the frame extends around the outer edges of the celluloid window and is secured thereto in the manner as clearly shown in 60 Figures 1 and 2.

The receptacle further includes a top structure designated generally by the numeral 6, and the same comprises two pieces of heavy elastic fabric denoted by the numerals 7 and 65 8, respectively.

These pieces are secured at their lower edges to the upper edges of the respective sides of the canvas body 2, and the end forming sections 9 and 10 of the pieces of elastic fabric 70 are stitched at their lower edges to the upper edges of the end forming walls of the body 2.

A runway engaging fastener construction designated generally by the numeral 11 is associated with the free edges of the top forming pieces 7 and 8, and cooperating with the runway forming element is the movable locking member 12. These runway forming elements extend from the top of the end wall 9 for the full length of the upper edges of the 75 pieces 7 and 8, and downwardly along the opposite end wall 10. A slit 13 is formed in the adjacent end wall of the body 2, and this slit extends downwardly from the upper edge of this particular end wall to the intermediate 80 portion thereof. An additional slit 14 is provided in the end wall 10 that extends from the termination of the runway forming element to the lower edge of the end wall, and this slit 14 registers with the slit 13, as clearly 85 shown in Fig. 2.

When the movable locking member of the fastening construction is in the position shown in Figures 1 and 2, the adjacent edges of the top forming pieces are secured together 90 whereby to entirely close the upper portion 95 of the receptacle.

Obviously when the movable member 12 of the fastener construction 11 is moved to the other end of the receptacle, the adjacent edges 100

of the top forming sections 7 and 8 are disconnected, and also the slit portion of the end walls of the receptacle and the top structure will be separated to permit access to the receptacle.

5 A receptacle of the above mentioned character is particularly adapted to be used in the transit of mail and will protect the letters or packages while in transit. The simplicity of
10 my improved receptacle enables the same to be manufactured at a very low cost, and yet will be strong and durable, and at all times positive and efficient in carrying out the purposes for which it is designed.

15 While I have shown the preferred embodiment of my invention it is to be understood that minor changes in the size, shape and arrangement of parts may be resorted to without departing from the spirit of the invention or
20 the scope of the appended claims.

Having thus described the invention, what I claim as new and desire to secure by Letters Patent is:—

25 In a shipping receptacle of the class described, a substantially rectangular shaped body, the top thereof being slit longitudinally along the central portion thereof, said slit extending from one end of the top and downwardly along the opposite end of the body to
30 a point adjacent the bottom of the body, and a closure for the adjacent edges of the slit portion of the top, the upper portion only of the slit end wall of the body being normally closed by said closure, the remaining
35 portion of the slit permitting access to the receptacle at the end thereof when the closure for the receptacle is in an operative position.

In testimony whereof I affix my signature.
ROY G. HUBBARD.
